CLAIM

The ornamental design for a steam generating cleaning implement, as shown and described.

DESCRIPTION

FIG. 1 is a front perspective view of a steam generating cleaning implement showing my new design;

FIG. 2 is a right side view thereof;

FIG. 3 is a front elevational view thereof;

FIG. 4 is a top plan view thereof;

FIG. 5 is a bottom plan view; and,

FIG. 6 is a rear elevational view.

The portion shown in broken lines in FIGS. 1-3 and 5-6 for illustrative purposes only and forms no part of the claimed design.
